(57) **CLAIM**

The ornamental design for an electronics fan, as shown and described.

DESCRIPTION

FIG. 1 is an isometric view of a top, front, and right side of an ornamental design for an electronics fan;

FIG. 2 is a front elevational view of the electronics fan of FIG. 1;

FIG. 3 is a rear elevational view of the electronics fan of FIG. 1;

FIG. 4 is a top plan view of the electronics fan of FIG. 1;

FIG. 5 is a bottom plan view of the electronics fan of FIG. 1;

FIG. 6 is a left side elevational view of the electronics fan of FIG. 1; and,

FIG. 7 is a right side elevational view of the electronics fan of FIG. 1.

The dash-dash-dash lines illustrate portions of the electronics fan that form no part of the claimed design.

1 Claim, 5 Drawing Sheets
